UNITED STATES PATENT OFFICE

94,731

DESIGN FOR A TRAY FOR A HIGH CHAIR

Ernest L. Bolster, Gardner, Mass., assignor to Chair Town Manufacturing Co., Gardner,
Mass., a corporation of Massachusetts

Application December 17, 1934, Serial No. 54,445

Term of patent 3½ years

To all whom it may concern:

Be it known that I, Ernest L. Bolster, a citizen of the United States, residing at Gardner, in the county of Worcester and State of Massachusetts, have invented a new, original, and ornamental Design for a Tray for a High Chair, of which the following is a specification, reference being had to the accompanying drawing, forming part thereof.

Fig. 1 is a perspective view of the article showing my new design;

Fig. 2 is a partial side elevation;

Fig. 3 is a partial bottom view, and

Fig. 4 is a partial front elevation.

I claim:

The ornamental design for a tray for a high chair as shown and described.

ERNEST L. BOLSTER.
